INDIVIDUAL POCKET-SIZE VENTILATING APPLIANCE

Homer C. Whiting, Opa Locka, Fla.

Application January 2, 1959, Serial No. 784,736

11 Claims. (Cl. 230—259)

The present invention provides certain improvements in small-sized portable blower or fan constructions intended for pocket transportation and individual ventilation.

It will be apparent that in many circumstances and environments it is desirable for an individual to have available some means for dissipating objectionable environmental contaminants, such as tobacco smoke, olfactory irritants, insects, or many other air-borne agencies of an irritating and objectionable character.

The present invention provides a miniature individual ventilating means which will effect dissipation of atmospheric contaminants from many environments, such as for example, from the interior of automobiles or other vehicles, for individual bedside ventilation or in many other locations where individual aeration and ventilation is desirable, without affecting other individuals in a close proximity thereto. The invention provides an individual ventilating assembly which readily is adapted to be carried in a pocket of a coat or other garment, and the assembly may be set up readily for use whenever and wherever individual ventilation is desired.

It has been found in practice also that the device of the present invention is highly useful as an aid to the treatment of the common cold and other respiratory afflictions, such as asthma and hay fever through concentrated dissemination of therapeutic agents for relieving respiratory congestion in the immediate environment of an individual sufferer therefrom.

A further object of the invention is to provide a miniature fan assembly of a kind somewhat resembling a conventional pocket flashlight except for requisite modifications of the base or cell-containing structure and replacement of a usual flashlight bulb by a motor which is driven by a single one and one-half (1½) volt flashlight cell or battery of a conventional type which is contained in a base housing that is compartmentized to adapt it to particular operating conditions, the motor rotating conveniently demountable fan blades which are made of a suitable plastic material, for example nylon, which material is sufficiently stiff so as to be self-sustaining, the fan blades being adapted to be demounted and stored, when not in use, in an air passage provided in the compartmentized base housing member in one of which compartments the flashlight cell which is the source of energy, is received, and from which air passage the blades may be removed readily and operatively mounted and assembled for desired service adjacent to an open forward end of the air passage through which the fan blades move gentle air currents for diffusing into the surrounding environment.

A further object of the invention is the provision of novel locking means in the base portion for retaining the flashlight cell in operative position in its compartment, while enabling ready removal of the cell whenever a change of the cell is desired, such as by replacement by a fresh cell upon exhaustion of the cell in service or for any other reason.

2

Another object of the invention is to so mount the motor and fan blades with respect to the base portion of the device, so that the air flow activated by the blades may be directed therefrom at different angles and directions depending upon which selected surface of the base portion of the device is used as a supporting base.

Further objects and advantages of the invention will become apparent as the description proceeds, and the features of novelty will be pointed out in particularity in the appended claims.

Structural details of a desirable illustrative embodiment of a device constructed in accordance with the instant invention are shown in the accompanying drawings, in which:

Fig. 1 shows a longitudinal sectional elevation of an illustrative embodiment of the structure of the present invention, the view illustrating essential structural details thereof;

Fig. 2 is a front end elevation of the device of Fig. 1;

Fig. 3 is a rear end elevation;

Fig. 4 is a longitudinal sectional view taken along the line 4—4 of Fig. 2, looking in the direction of the arrows;

Fig. 5 is a longitudinal sectional view taken along the longitudinal center line of the device, the view being somewhat similar to the showing of Fig. 4, but showing further structural details of the base member and of the mounting of the flashlight cell and a control switch for operating the fan-driving motor;

Fig. 6 is a vertical elevation showing the ventilating appliance resting on end on a surface with the fan blades of the appliance directed upwardly, as for bedside ventilation, the view showing the appliance resting on a resilient cushioning end of its outer housing, such cushioning end protecting a polished surface of a supporting medium against damage;

Fig. 7 is a view similar to Fig. 6 except that the appliance is resting on its side with respect to the surface of its supporting medium, and with the fan blades directed to blow air currents in an upwardly direction;

Fig. 8 is a view similar to Fig. 7 but with the appliance resting on its opposite side with respect to the showing of Fig. 7, the fan blades being directed downwardly and being in opposite direction with respect to Fig. 7.

Before proceeding with a detailed description of the present invention, it may be pointed out that the original conception thereof arose from the need for a self-powered, self-contained individual pocket-size ventilating device which is usable in any location or environment from which it is desirable to dissipate unpleasant odors originating from any source which an individual may encounter while at work, or while traveling, or in any other situation, to repel insects, to replace obnoxious atmospheric constituents with pleasant smelling perfume, deodorizing materials, therapeutic agents, or other volatile substances placed within proper proximity to the fan blades, the action of the latter properly mixing such vapors of volatile substances with a strong, narrow air stream which is blown by the fan blades directly to the individual user, while being unobjectionable to any neighboring associate. Volatile therapeutic agents for relieving respiratory conditions such as asthma, hay fever, sinusitis, colds may be employed gratefully by an individual sufferer therefrom, the device being adapted to afford such an individual quick and pleasant relief, or

as an insect repellent, with or without an insect repelling material. The propeller or fan blade is driven by a small motor which is actuated by a conventional flashlight battery contained in a housing which provides a narrow air channel to the fan blade which channel provides a storage space for the fan blade when the ventilating device of the invention is not in service.

Referring more particularly to the drawings the individual ventilating device of the present invention which, as has been mentioned above, is designed and intended to be carried, when not in use, in a pocket of a coat or other garment, comprises a relatively heavy and sturdy base portion which includes an outer housing 1, composed of a pliable plastic or rubber material which is open at opposite ends and which is illustrated as being preferably substantially rectilinear in cross-section and which receives a multicompartimented insert 2, which is composed of a metal, which insert 2 is fitted into housing 1 through one of the opposite open ends of the housing, the insert 2 being somewhat shorter in its over-all length than the housing 1, and being of outer cross-sectional dimensions approximately equal to the inner cross-sectional dimensions of the housing 1, so that the insert 2 may be retained in place frictionally by engagement with housing 1, as shown in Fig. 4.

The insert 2 is fabricated from a single piece of moldable material such as metal, as noted above and is divided interiorly into a plurality of compartments or sections, one of which defines an open-ended air channel or passage 3, enabling a free flow of air currents therethrough, a substantially circular battery or cell receiving compartment 4, and an open-ended base portion 5. The channel 3 is shown as having a substantially rectilinear upper portion closed by a continuous top 6, the upper portions 7 of the sidewalls being parallel, while the lower portions 8 converge inwardly to crimping 9 which separates the upper channel 3 from the circular battery-receiving section or compartment 4, the periphery of this latter being crimped as is indicated at 10 to define the base portion 5, which is formed by folding the opposite sides of the inert one over the other and in engagement as shown at 11 in Fig. 2. A conventional flashlight cell 12 is receivable in the intermediate battery-receiving compartment or section 4 through the open rear end thereof.

Normally the rear end of this compartment 4 is closed by a removable locking plate 13, which is a discal closure plate which is provided for closing the rear end of the compartment 4 to retain the inserted battery cell 12 in place in its compartment 4, the locking plate 13 being made of suitable metal and being releasably held in place by snap locks 14 pressed against the plate 13, from the insert 2, thereby leaving in the insert corresponding snap-lock holes 15.

The locking plate 13 has as an integral part a folded operating handle 16, as is shown in Fig. 4. A screw 17 is threaded into this handle 16, the head of which screw is adjacent to the inner surface of the locking plate, and forms a retaining member for a compressed coil spring 18, which spring bears against the bottom of the flashlight cell or battery 12, and continuously urges the battery forwardly, so that the exposed contact end 19 of the conventional center electrode will be pressed into close electrical contact with contact 20 of a sliding control switch 21 which controls operation of the motor by actuation of sliding switch handle 22.

The locking plate 13 is releasable from its locking position with respect to the cell compartment 4 of the insert 2 by turning the locking plate relatively to the insert, following release of the snap lock 14, until the opposite peripheral recesses 14' in the locking plate clear the snap lock 14. This enables the locking plate 13 to be lifted out by the handle 16, thereby releasing the battery 12 for removal from its compartment or section 4 in the insert 2 for replacement by a fresh cell whenever such replacement may be required.

The control switch 21 which has been mentioned above, is mounted on two angle members 24, each of which is secured by a rivet 26. The switch 21 is secured to the angle member 24 by two sheet metal screws 25 threaded into the angle members. The switch 21 is self contained and provides its own metal strip 23 between

the angle members. The actuation of the switch 21 is operated between the open and closed positions.

This control switch 21 is connected electrically by a lead 29 to a motor 30 which is mounted on a channel yoke 31 that extends back into the air channel or passage 3 for substantially the entire length of the passage for stability. This yoke 31 projects forwardly from the housing and has its forwardly-projecting portion bent upwardly at an angle with respect to the portion of the yoke extending into the air passage 3, as is indicated at 31', this angle of bend being approximately 25 degrees, so that the motor 30, which is removably mounted adjacent to the free end of the yoke 31 and which is grounded to the yoke by a ground lead 32, and while also has mounted on its shaft 33, a propeller-type fan or blower 34, this fan 34 being inclined likewise to the horizontal at substantially this same angle of 25 degrees, so that the air flow through the air passage 3 may be directed selectively by the blower 34 at different directions and angles with respect to the body of the device, depending upon which surface of the device is used as a supporting base, which surface may be an upper surface, a lower surface, or an end surface.

As to this fan or blower 34, it comprises oppositely-extending propeller-type blades 35, which preferably are composed of a plastic, such as nylon, for example which has been stiffened so as to be self-sustaining in shape. These blades 35 are mounted adjacent to the forward open end of the restricted air passage 3, so that when the fan 34 is operating, the blades 35 draw air through the passage 3, and gently diffuse such air into the surrounding atmosphere. Nylon fan blades 35 are pliable in nature and are desirable for use in connection with the instant device, since such material is incapable of causing damage to persons or objects during operation and are entirely adequate to draw gentle air currents through the passage 3 and to diffuse such air into the surrounding environment for dispersing smoke or other obnoxious constituents which may be present in such environment.

The air passage 3 also may be utilized to receive a body of absorbent material, such as absorbent cotton, or the like, indicated at 40, which may be saturated with a volatile therapeutic agent or a perfume which will be evaporated by and enter the gentle air currents which are being drawn through the air passage 3 by the blades 35, such material being dispersed and diffused into the ambient environment along with the air which is being dispersed by the blades 35.

In addition to drawing air through air passage 3, the blades 35, which rotate at a speed of approximately 2500 r.p.m. draw air through channels 37 intermediate the housing 1 and insert 2, such channels serving as auxiliary air passages for implementing air being drawn through the principal air passage 3.

As has been mentioned above, the blades 35, being composed of nylon or other plastics, do not require a guard; and the motor housing may be secured to the yoke 31 by screws 39, which may be removed readily to enable convenient removal of the motor from the yoke 31 whenever it may be found desirable to do so.

It has been mentioned above that an advantageous object of the instant invention is to so mount the motor and fan blades with respect to the base portion of the instant appliance so that the air flow activated by the blades may be directed therefrom at different selected angles and directions depending upon which selected surface of the base portion of the device is used as a supporting base. This feature is of particular advantage for the use of the instant appliance as a bedside ventilator, as it is substantially entirely free from vibration, and it will remain in its selected position for indefinitely long operational time periods without requiring attention.

Figs. 6, 7, and 8 are illustrative of this circumstance. In these views, the ventilator of the instant invention is shown as resting on a support 41, which may have a

polished top surface 42. The outer housing 1 of the ventilator is somewhat longer than the insert 2, and forms a sleeve for the latter which has an end overlap 36, and as the outer housing 1 is made of a soft material such as soft rubber, or a soft leather or fabric, this end overlap 36 forms a cushion seat for the appliance when the latter is placed on end on surface 42, in the position shown in Fig. 6, in which end position the fan blades 35 direct the air currents in an upward direction at the aforesaid angle of approximately 25 degrees to the vertical. The interposition of cushioning end overlap 36 between surface 42 of support 41 and insert 2 in housing 1 obviates any tendency of the surface 42 to become scratched or marred otherwise because of the presence of the insert 2 thereon. Also, in the position of the ventilating appliance illustrated in Figs. 7 and 8 the soft outer housing 1 obviates any tendency of the ventilating device to scratch or mar polished surface 42 of supporting member 41, the illustration of Fig. 7 showing the ventilator lying on one of its sides on the surface 41 so that the blades 35 will act to direct air currents at an inclined angle of 25 degrees to the horizontal in an upward direction, while in Fig. 8 the ventilator is shown as lying on an opposite side with reference to Fig. 7, so that the blades will direct air currents oppositely to the showing of Fig. 7, and downwardly at an angle of approximately 25 degrees to the horizontal. From these views, the versatility of the ventilating appliance of the instant invention becomes immediately apparent, it being adaptable to a multitude of desired usages.

The foregoing detailed description and the accompanying drawings are directed to a preferred illustrative embodiment of the present invention, structural details of which however, may be modified as may become suggested to one skilled in the art without departing from the inventive concept. Accordingly, it will be understood that it is intended and desired to include within the scope of this invention such modifications and changes as may be necessary or desired to adapt the invention to varying conditions and uses as defined by the scope of the appended claims.

Having described my invention what I claim as new and desire to secure by U.S. Letters Patent is:

1. A pocket-size individual ventilating appliance adapted to be carried in a pocket of a coat, which comprises, in combination, a housing, an insert member in the housing defining an air passage, a compartment for receiving a flash-light dry cell, and a base section, a flash-light cell in the compartment, a yoke extending into the air passage, the said air passage being open at opposite ends, there being an open forward and an open rear end, a motor mounted on forward portion of the yoke, a control switch mounted on the insert member, electric leads connecting the motor to the switch and to the yoke, and plastic propeller-type fan blades mounted on the motor adjacent to the forward open end of the air passage for drawing air currents through the passage and diffusing the currents into surrounding air closely adjacent to an individual user of the appliance.

2. A portable pocket-size individual ventilating appliance adapted to be carried in a pocket of a coat, which comprises, in combination, a housing, an insert member in the housing having an open forward end and an open rear end, and defining a restricted air passage, a compartment for receiving a flash-light dry cell, and a base section, the housing having an open front end and an open rear end corresponding to the open ends of the insert member, a flashlight cell in the said compartment, a rotatable locking plate for retaining the cell in the compartment, releasable locking means on the insert engaging the locking plate, the locking plate having diametrically opposed recesses adapted to clear the locking means responsively to rotation of the locking plate for enabling removal of the locking plate for removal and replacement of the flashlight cell, a yoke extending into

the air passage, a control switch mounted on the forward end of the insert member, a motor on the yoke electrically connected to the switch and to the yoke, plastic propeller-type fan blades mounted on the motor for drawing air through the air passage and disseminating the said air adjacent to an individual user of the appliance and a control handle for actuating the switch between open and closed positions for controlling actuation of the motor.

3. The appliance as claimed in claim 2 wherein the insert member and housing define between them auxiliary lateral air passages supplementing the air passage in the insert member.

4. The appliance as claimed in claim 3 wherein the housing is enclosed in a cushioning sleeve having an end overlap for enabling the appliance to be placed in upright position on a polished surface for operation without likelihood of damage to the surface.

5. The appliance of claim 2 wherein the yoke has forward position inclined outwardly relative to the housing and the motor is mounted on the inclined portion of the yoke.

6. The appliance of claim 2 wherein the fan blades are composed of a plastic material.

7. The appliance of claim 5 wherein inclined portions of the yoke are off-set at an angle of approximately 25° to the horizontal.

8. A pocket size individual ventilating appliance adapted to be carried in a pocket of a coat, which comprises, in combination a base portion defining a main air passage and a compartment for receiving a flashlight dry cell, the base portion having a plurality of surfaces upon any selected one of which the base portion may rest when the appliance is in service, a flashlight dry cell in the said compartment, a yoke extending into the air passage and projecting outwardly therefrom, a motor mounted on outwardly projecting portions of the yoke, fan blades rotatably mounted on the motor for rotation by the motor, outwardly projecting portions of the yoke being bent upwardly to so mount the motor and fan blades with respect to the base portion that air currents drawn by the fan blades through the air passage may be directed selectively in different directions with respect to the base portion depending upon which surface of the base portion is used as a supporting surface, which surface may be selectively an upper surface, a lower surface, and an end surface, and electrical connecting means connecting the flashlight dry cell in the base portion and the motor for actuating the motor, the electrical connecting means including a switch for controlling operation of the motor.

9. A pocket size individual ventilating appliance as claimed in claim 8, wherein the base portion includes a soft open-ended cushioning outer housing enclosing the base portion and extending beyond an end thereof to define an end overlap whereby the base portion is cushioned with respect to a supporting surface independently on whatever surface of the base portion the appliance may rest when in service.

10. A pocket size individual ventilating appliance as claimed in claim 8 wherein the base portion includes a main air passage and auxiliary air passages, and wherein the yoke removably extends into the main air passage, while having forward portions extending therefrom, the motor and fan blades being carried by forward extending portions of the yoke and adjacent to the air passages for drawing air currents through the passages and distributing such currents into surrounding environment.

11. A pocket size individual ventilating appliance as defined in claim 8 wherein the air passage includes a porous carrier impregnated with a volatile air-treating material adapted to be volatilized by air currents drawn through the air passage by the fan blades and disseminated thereby into a surrounding environment.
